CLAIM

The ornamental design for a charging cradle as shown and described.

DESCRIPTION

FIG. 1 is a front perspective view showing a charging cradle; FIG. 2 is a rear perspective view thereof;

FIG. 3 is a top plan view thereof;

FIG. 4 is a front view thereof;

FIG. 5 is a right side view thereof;

FIG. 6 is a left side view thereof;

FIG. 7 is a rear view thereof; and,

FIG. 8 is a bottom plan view thereof.

In the drawings, the broken line showings are for the purpose of illustrating environmental structure or portions of the charging cradle that form no part of the claimed design.

1 Claim, 3 Drawing Sheets
